**AUDIBLE SIGNAL DEVICE FOR INDICATING
MOVEMENT OF A GAME PIECE**
Joseph B. Büdi, 287 Scarlett Road, Toronto 9,
Ontario, Canada
Filed Sept. 13, 1963, Ser. No. 308,817
14 Claims. (Cl. 273—137)

This invention relates to an indicating gamepiece, and more particularly to a gamepiece which is capable of providing an unmistakable audible indication of untoward interference therewith by a player.

A great many games are known which involve the movement of gamepieces over an appropriately marked board in accordance with an established set of rules. One such game, enjoying widespread popularity, is that known as "chess."

Owing to the complicated nature of some of these games, it will often happen that a player will change his mind while actually engaged in moving a gamepiece and will decide that some alternative move is preferable. However the rules of such games specifically prohibit any such indecision and the player is generally obliged to consummate any move, once initiated, or else incur some form of penalty.

A certain difficulty therefore arises in determining whether a player has actually commenced to move a gamepiece, or whether the gamepiece has merely been touched by the player without, however, incurring any actual movement thereof.

Accordingly various attempts have been made to devise some form of signalling device which will provide definite indication as to whether a gamepiece has actually been interfered with to an extent sufficient to penalize a player, whereby a player cannot argue that he has not initiated or completed a move once presented with said definite indication to the contrary.

Prior art attempts to devise an indicator for gamepieces have tended to resort primarily to electrical principles, whereby indication results from breaking of contact between the gamepiece and board, or in moving the gamepiece from an electrically conductive section of the board to an insulative section, etc. Such electrical indicating systems are relatively expensive in construction however and embody several obvious disadvantages such as the necessity to safeguard the players against electrical shock, the lack of portability due to reliance on electrical mains, the need for replacement of batteries when such are used to render the board portable, and the ever-present possibility of an electrical system being rendered inoperative by dust or corrosion without either player being aware that the game is no longer being monitored to provide the intended indication of infractions of the rules.

Although there has been some realization of the inadequacies inherent in such electrical systems for indicating infractions, there has apparently been little incentive in the art to investigate alternative systems. For instance such attempts as have been made to employ mechanical systems for such indication purposes have tended to rely on inertial principles, whereby the gamepiece must be subjected to a relatively abrupt jolt before sufficient acceleration is present to actuate the sensor, which is usually arranged to be a spring-mounted bob or similar bell-clapper mechanism capable of providing an audible indication.

Hence these inertial systems previously employed for indicating infractions have generally not been sufficiently sensitive to provide the necessary reliable indication of infractions when such infractions result from a relatively gradual movement of a gamepiece whereby the acceleration remains below a detectable level.

2

Accordingly it is an object of the present invention to provide a movement indicator particularly suitable for certain gamepieces, which will detect infractions of the rules of play, without exhibiting any of the aforementioned shortcomings.

It is also an object of the invention to provide a movement indicator for gamepieces which is of a simplified construction enabling economical incorporation in said gamepieces.

It is a further object of the invention to provide a move-indicator for gamepieces which ensures a reliable indication of both the initiation and completion of a move, irrespective of the speed with which the gamepiece transferred over the board.

It is a still further and important object of the invention to provide an indicating mechanism for a gamepiece whereby a audible and unmistakable signal is given whenever the gamepiece is raised or lowered on the board.

It is particularly, though not exclusively, an object of the invention to provide an audible move-indicator for chessmen.

Still another important object of the invention is to provide an audible move-indicator for gamepieces which will readily conform to the configuration thereof without any adverse effect on the appearance of the gamepiece.

Briefly therefore the invention contemplates providing a gamepiece with a weight-actuated striker mechanism wherein the weight moves in response to raising or lowering of the gamepiece and is coupled to the striker through gearing whereby the movement of the weight relative to the gamepiece may be considerably amplified to drive the striker against a chiming member, such as a bell. For a more comprehensive appreciation of the aims and objects of the invention however, reference is made to the ensuing description and claims wherein—

FIG. 1 is a perspective sectional view of a gamepiece of the chess variety incorporating the novel audible move-indicator of the invention.

FIG. 2 is a partially-sectioned elevational view of the novel gamepiece of FIG. 1 and;

FIG. 3 is a cross-sectional view taken in the plane 3—3 of FIG. 1.

Considering the preferred form of the novel audible move-indicator of the invention which is illustrated by way of example, there is shown a conventional top 6 suitably contoured to identify the gamepiece 7 as to type. In the particular example shown in FIGS. 1 and 2 for instance the gamepiece will be recognized as a chessman of the "castle" variety. The gamepiece 7 has an external contour which is essentially conventional and is allowed to rest upon a conventional gameboard 8.

According to the invention however an audible chiming member 9 is suspended about the gamepiece 7 and may take the form of a resonant metallic ring 9 as shown. The chiming ring or bell 9 is disposed adjacent a striker 10 which is shown in FIG. 1 as having a T-bar configuration in cross section. The resonant ring 9 is conveniently located within the confines of an annular channel 11, which is defined between a lower flange 12 of the identification top 6 and a shoulder 13 of the gamepiece 7. It will be realized that the chiming ring 9 must not be unduly constrained, otherwise the resonant properties thereof would not become fully effective to produce a distinct chime. A suitable means whereby resonant ring 9 may be loosely suspended within the confines of channel 11 is the coil-springs 14 on the gamepiece 7. The sounding ring 9 may then be attached to the springs 14 in any known manner and thus are carried by the gamepiece 7 without occasioning any appreciable damping of the resonant sound produced.

The flange 15 of the striker 10 is slidably supported

within a horizontal slot 16 which has both ends thereof opening into channel 11 whereby they face directly onto the sounding ring 9. The web portion 17 of striker 10 has ratchet teeth provided therealong as shown in FIGS. 1 and 2, whereby said striker may be propelled along slot 16 by driving mechanism about to be described.

The rack teeth of ratchet portion 17 of striker 10 are arranged to mesh with peripheral teeth on a segmental gear or pinion 18, which segmental gear or pinion 18 is arranged to be supported as on a shaft 19. Shaft 19 is conveniently journalled in the hollow body of gamepiece 7, and a pitman or crank 20 is eccentrically coupled to pinion 18 as by a pivot pin 19a. A similar pivot pin 19b is employed to couple the remaining end of crank 20 to an actuating weight 21, which is slidably housed in the base of gamepiece 7.

The driving weight 21 is provided with a peripheral flange 22, in sliding contact with the interior of gamepiece 7, whereby weight 21 is smoothly guided in a vertical direction. The flange 22 also serves to limit the extent of vertical movement of the driving weight 21 within a groove 23 defined between a retaining disc 24 and a shoulder 25a within base 25 of the gamepiece body.

It will thus be apparent that, with the disclosed construction, upon raising gamepiece 7 from the surface of board 8, the actuating weight 21 will drop downwardly under the action of gravity, thereby causing the associated pitman or crank 20 and pinion 18 coupled thereto to move in the direction of arrows 26. Weight 21 thus descends to the extended position of FIG. 2, causing the gear segment and rack teeth to project striker 10 against the left-hand portion of the sounding ring 9, with consequent sounding of an audible note thereby.

In a similar manner it will be evident that, upon resetting gamepiece 7 back onto the surface of board 8, the weight 21 is forced to retract within the interior of gamepiece 7 once again, whereupon the segmental gear and meshing rack teeth are now moved in the opposite direction to the arrows 26, thereby causing projection of striker 10 against the right-hand portion of sounding ring 9; i.e. 40 reversely to the direction of travel of striker 10 when the gamepiece was raised.

It will thus be seen that the novel move-indicator of the invention does not depend on a "bob and spring" or similar acceleration responsive device, but instead will respond to vertical displacement of the gamepiece even when such movement is extremely gradual such that the acceleration is negligible.

Moreover it should be realized that with suitable gearing of rack and pinion 17, 18, and by selecting appropriate eccentricity of pivot pin 19a relative to shaft 19 for example, it is possible to increase the travel of striker 10 in response to movement of its driving weight 21. Thus the sensitivity of the striker to motion of its driving weight is readily increased whereby even a minute movement of the driving weight is sufficient to impel the striker across the diameter of the sounding ring with appreciably amplified speed, to firmly strike the delicately suspended resonant ring 9 and cause an audible reverberation thereof.

Both the identifying top 6, and the actual gamepiece 7 employed to house the sounding mechanism, may be formed of any suitable material as, for example, an attractively coloured plastic. The components 6 and 7 may be fastened together in any convenient manner following assembly of striker 10 and resonant ring 9 thereon. The suspension springs 14 may be attached to ring 9 by any convenient means such as brazing and may be mounted on gamepiece 7 simply by insertion into recesses 14a therein as shown in FIG. 3.

It should be realized that while the invention has been illustrated and described with reference to a selected structural arrangement thereof it will be appreciated that such changes and variations may be resorted to as fairly come within the scope of the appended claims.

What I claim is:

1. A combined gamepiece and audible movement indicator therefor comprising a resonant ring suspended substantially symmetrically about said gamepiece, a striker slidably borne by said gamepiece adjacent to said ring, an actuating mechanism housed within said gamepiece, said actuating mechanism including an oscillatory member pivotally supported on said gamepiece and mechanically connected to said striker for projecting it against said ring to produce an audible signal, and a weight loosely confined in an opening in the base portion of said gamepiece and movable outwardly thereof by gravity when said gamepiece is raised from a supporting surface, and coupling means connecting said weight to said oscillatory member for actuating the latter when said weight moves outwardly.
2. The structure of claim 1, wherein said striker is coupled to said oscillatory member through gearing means.
3. The structure of claim 2 wherein said gearing means includes a toothed rack on said striker in mesh with a gear segment on said oscillatory member.
4. The structure of claim 1, wherein said resonant ring encompasses said gamepiece, and wherein said striker is transversely supported to move endwise within the confines of said ring.
5. The structure of claim 4, said striker having a T-shaped cross section by which it is slidably engaged in a slot of a conforming cross section provided in said gamepiece.
6. The structure of claim 1 wherein said ring is suspended about said gamepiece by means of coil springs.
7. The structure of claim 6, wherein said ring is loosely confined within an annular channel concentric with said gamepiece.
8. The structure of claim 1 wherein said actuating mechanism comprises a crank and pinion, said crank being pivotally coupled to said weight and eccentrically pivoted to said pinion, and wherein said pinion is in mesh with rack teeth on said striker.
9. A gamepiece for movement on a playing board, said gamepiece comprising a chambered body having a base portion and an upper portion, said upper portion provided with an encompassing groove, a ring-like resonant element confined in said groove, means loosely supporting said resonant element in said groove, a transverse slot provided in said upper portion of the body and open at its ends to said resonant element, a striker supported in said slot for endwise movement therein, said striker having rack teeth, a gear segment pivoted in said chambered body and having toothed engagement with said rack teeth, a pitman having an upper end and a lower end, said upper end pivoted to said gear segment radially of its pivotal axis, a weight member vertically displaceable in an opening provided in the base portion of said body, said weight member pivoted to said lower end of said pitman.
10. The structure of claim 9 wherein said gear segment is carried on a shaft, said shaft supported transversely of said body and interiorly thereof.
11. The structure of claim 9 wherein said striker has a cross section of T configuration providing flanges by which it is slidably confined for reciprocal movements.
12. The structure of claim 9 wherein said rack teeth are formed on a web portion of said striker.
13. The structure of claim 9, wherein said gamepiece is surmounted by an identifying top assembled thereto.
14. The structure of claim 13, wherein said gamepiece is provided with a shoulder remote from said board and said top is provided with a flange, said shoulder and flange defining said encompassing groove therebetween.
